UNITED STATES PATENT OFFICE.

ENOCH GEORGE, JR., OF PITTSBURGH, AND ISAAC H. MILLIKEN, OF ASPINWALL, PENNSYLVANIA, ASSIGNORS TO THE McCONWAY & TORLEY COMPANY, OF PITTSBURGH, PENNSYLVANIA, A CORPORATION OF PENNSYLVANIA.

COUPLING AND YOKE CONNECTION.

1,399,610.

Specification of Letters Patent.

Patented Dec. 6, 1921.

Application filed July 30, 1920. Serial No. 399,993.

To all whom it may concern:

Be it known that we, ENOCH GEORGE, Jr., and ISAAC H. MILLIKEN, citizens of the United States, residing, respectively, at 5 Pittsburgh, in the county of Allegheny and State of Pennsylvania, and Aspinwall, in the county of Allegheny and State of Pennsylvania, have invented certain new and useful Improvements in Coupling and Yoke 10 Connections; and we do hereby declare the following to be a full, clear, and exact description of the invention, such as will enable others skilled in the art to which it appertains to make and use the same.

15 Our invention relates to a coupler and yoke connection embodied in a draft appliance for railway cars, and is especially designed to enable couplers of the type commonly attached to cars without capability of 20 lateral swinging movement, to be applied to passenger or other cars where a pivotal movement of the coupler with respect to the car is desired.

The primary object of the invention is to 25 afford a strong, durable and efficient operating mechanism which may be economically manufactured. In its principal aspects this object is accomplished, generally stated, by incorporating in an intermediate member, 30 through the intervention of which the coupler and draft yoke are connected, structural features effecting a disposition of metal approximately in the lines of strain communicated from the yoke when the mechanism is 35 subjected to draft, and by constructing the rear end of the intermediate member so as to afford ample strength for the transmission of buffing shocks and at the same time prevent undue increase in the compression 40 of the springs of the draft gear incident to lateral swinging of the coupler with respect to the draft yoke. The construction also facilitates efficient manufacture in that it provides for core openings enabling the 45 intermediate member to be cast by the use of a single core.

In the drawings illustrating the preferred embodiment of the invention, the scope whereof is pointed out in the claims,—

50 Figure 1 is a plan view of a coupler and yoke connection involving the invention, the

forward end of the car coupler and a portion of the draft yoke being omitted.

Fig. 2 is a side elevation of the construction shown in Fig. 1.

Fig. 3 is a vertical section on the line 3—3, Fig. 1.

Fig. 4 is a detail section on the line 4—4, Fig. 2.

Fig. 5 is a detail section on the line 5—5, Fig. 2.

In the drawings, 1 indicates the stem of a car coupler and 2 a draft yoke. The stem 1 of the coupler is of a well known type which is commonly attached to the yoke or 65 draft links of the draft rigging by means of a key, said stem being for that purpose provided near its rear end with a transverse horizontal key slot 3. The form of yoke illustrated in the drawings is also of a well 70 known type involving longitudinally extending vertically spaced arms 4 which are provided at their forward ends with vertically aligned openings 5 adapted to receive a pin 6 for pivotally connecting the draft yoke to 75 the intermediate member 7 of the mechanism. The cushioning unit of the draft gear (not shown), which may consist of the usual followers and interposed springs, is adapted to be received between the arms 4 of the 80 draft yoke 2.

The member 7 which is intermediate of the coupler and yoke is provided at its forward end with oppositely disposed portions 8 which are adapted to receive the rear end 85 of the coupler stem between them and which are formed with horizontally aligned slots 9 corresponding to the transverse slot 3 in the coupler stem. A key 10 passing through the slot in the coupler stem and those in the 90 intermediate member 7 serves to connect the coupler to the intermediate member. If desired cotters 11 which pass through the key 10 outside of the intermediate member 7 may be employed to retain the key in assembled 95 position.

The slotted portions 8 of the intermediate member are integrally united at their rear ends by a transversely extending wall 12 adapted to engage the rear end of the coupler 100 stem 1 and to receive the buffing shocks transmitted by the coupler; and it is preferred

also to unite the slotted arms 8 by upper and lower webs or plates 13 which, in conjunction with the rear portions of the said arms 8, form a socket 14 for the reception of the 5 rear end of the coupler stem 1.

The intermediate member 7 is preferably provided at its rear end not only with a pivot lug 15 in horizontal alinement with the coupler stem, but also with upper and lower 10 pivot lugs 16 and 17, respectively, which are spaced vertically from the central lug so as to allow the forward ends or pivot lugs 4^a of the arms 4 of the draft yoke to mesh with the several pivot lugs 15, 16 and 17. The 15 central pivot lug 15, which is preferably hollow, is provided with vertically alined openings 18 forming a pivot pin hole for the reception of the pivot pin 6, and the upper and lower pivot lugs are provided with correspondingly alined pivot pin openings 19 20 and 20, respectively.

In order to protect the pivot lugs 4^a of the draft yoke from injury in buffing the central lug 15 is preferably extended rearwardly somewhat beyond them, as illustrated in Figs. 2 and 3, so that the entire buffing shock is communicated to the front follower of the cushioning unit (not shown) of the draft rigging through the lug 15 exclusively.

The pivot lug 15 preferably is gradually reduced in width rearwardly from the transverse wall 12 to the pivot pin openings 18 and continues at such reduced width to its 35 rear end, the reduction in width of the end wall 21, which is adapted to abut the front follower (not shown) of the draft rigging, thus preventing undue compression of the draft springs when the coupler and intermediate member 7 execute pivotal movements with respect to the draft yoke 2. The contraction in width of the pivot lug 15 is 40 preferably effected by forming said pivot lug with rearwardly converging side walls 45 22 which are integrally united at their forward ends by the transverse wall 12 which separates the coupler receiving socket 14 of the intermediate member from the interior of the central pivot lug. The inclined walls 50 or webs 22, it will be observed, are disposed approximately in the lines of the draft strains which are communicated to the intermediate member 7 by the coupler and transmitted by said intermediate member to the 55 pivot pin 6 and thence to the draft yoke 2, thus attaining great strength and at the same time preserving substantial uniformity of thickness of metal, which is desirable in that shrinkage cracks and similar defects in the 60 casting are largely obviated. For a kindred reason the upper and lower pivot lugs 16 and 17, respectively, are preferably integrally united to the central pivot lug 15 on opposite sides by rearwardly converging 65 webs 23, the said webs 23 terminating at a

sufficient distance from the pivot pin openings in the pivot lugs to avoid interference with the forward ends of the arms 4 of the draft yoke when the coupler executes a lateral swinging movement.

The transverse wall 12 of the intermediate member may advantageously be provided with an opening 24 affording communication between the coupler receiving socket 14 and the interior of the hollow pivot lug 15. This 70 opening permits the intermediate member 7 to be made by the use of a single core, as will be readily understood. In order to facilitate anchoring this core it is preferred to provide the end wall 21 of the pivot lug 15 with an opening 25.

The pivot pin 6 is preferably designed to be downwardly removable. To maintain it in assembled position the lower pivot lug 17 may be integrally provided with a supporting bracket 26 upon which is slidably mounted a plate 27 on which the lower end of the pivot pin rests. By sliding the supporting plate 27 from beneath the pivot pin the latter may be withdrawn. This means for supporting the downwardly removable pivot pin in assembled position is well known and is merely illustrated as a convenient means which may be employed for that purpose.

We claim:

1. In a device of the character indicated, the combination with a coupler having a slotted stem, of a draft yoke, a member intermediate of said coupler and yoke and pivotally connected to the latter, a key for 95 connecting said coupler and intermediate member, and means for pivotally connecting said intermediate member and yoke, said intermediate member being provided at its forward end with oppositely disposed slotted portions adapted to receive the coupler stem between them and being provided at its rear end with a plurality of perforated pivot lugs which are integrally united on opposite sides by rearwardly converging webs.

2. In a device of the character indicated, the combination with a coupler having a stem, of a yoke having longitudinally extending arms provided with pivot pin openings at their forward ends, a member intermediate of said coupler and yoke provided with a transversely extending wall adapted to engage the rear end of said coupler stem and having a pivot lug adapted to extend between and be pivotally connected to said 115 yoke arms, means for connecting said coupler and intermediate member, and a pivot pin extending into said pivot lug and pivot pin openings, said pivot lug being provided with rearwardly converging side walls which 120 are integrally united by said transversely extending wall.

3. In a device of the character indicated, the combination with a coupler having a stem, of a yoke having vertically spaced 125

- portions provided with alined pivot pin openings, a member intermediate of said coupler and yoke provided at its rear end with a hollow pivot lug adapted to extend 5 between said vertically spaced portions of said yoke, means for connecting said coupler and intermediate member, and a pivot pin extending into said pivot lug and pivot pin openings said intermediate member being provided with a transverse wall intervening between the rear end of said coupler stem and the interior of said hollow pivot lug, and said pivot lug being of less width 10 at its rear end than at its forward end.
- 15 4. In a device of the character indicated, the combination with a coupler having a stem, of a yoke having vertically spaced portions provided with alined pivot pin openings, a member intermediate of said coupler 20 and yoke provided at its rear end with a plurality of spaced pivot lugs having vertically alined perforations, means for connecting said coupler and intermediate member, and a pivot pin extending into said pivot 25 pin openings and said pivot lugs, one of
- said pivot lugs being adapted to extend between said vertically spaced portions of the yoke and being provided with rearwardly converging side walls, and said intermediate member having rearwardly converging webs 30 integrally connecting the adjacent pivot lugs.
5. A member adapted for pivotally connecting the stem of a car coupler to a draft yoke, said member having a transverse wall 35 adapted to engage the rear end of the coupler stem and having at its rear end a plurality of spaced perforated lugs adapted to receive a pivot pin for connecting a draft yoke thereto, one of said pivot lugs being in horizontal alinement with said transverse wall and being formed with a rear end adapted to abut the forward follower of a draft rigging and having on opposite sides rearwardly inclined webs integrally united to 40 45 said transverse wall.

In testimony whereof we affix our signatures.

ENOCH GEORGE, JR.
ISAAC H. MILLIKEN.
